UNITED STATES PATENT OFFICE.

THOMAS A. HUTCHINSON, OF NEWARK, NEW JERSEY.

HAND BLOTTER.

Application filed January 23, 1922. Serial No. 531,139.

To all whom it may concern:

Be it known that I, THOMAS A. HUTCHINSON, a citizen of the United States, and a resident of Newark, in the county of Essex and State of New Jersey, have invented certain new and useful Improvements in Hand Blotters, of which the following is a specification.

This invention has reference to a device 10 adapted to be placed on the hand to hold a piece of blotting strip, and which will so carry the blotter that it can swing from a position under the fingers in which it can be used to blot writing on any object, to a position 15 at the rear of the hand and against the wrist; whereby the writer can hold the pen in the usual position without any interference, and when it is desired to blot the written matter, the blotter is simply swung to the forward position against the fingers, and by them pressed on the writing while at the same time the pen can be retained in the hand or fingers of the writer in its usual position.

20 A further object of the invention is to provide a device of this character in which the blotting piece is carried by a swinging member that will retain the blotter in each of the two positions.

25 Another object of the invention is to provide a lug or arm on the swinging member that can be readily engaged by a finger not used to grasp the pen, whereby to swing the blotter from the rear position to the forward position to blot the written matter.

30 A further object of the invention is to provide means for readily attaching a piece of blotting paper to the holder, and which can be readily manipulated to open the jaws that grasp the blotter.

35 In the accompanying drawing showing one embodiment of my invention, Fig. 1 shows the device in use carried by the hand and in the rear position.

40 Fig. 2 shows the blotter brought forward for use.

45 Fig. 3 is a partial view enlarged of the device separated from the hand.

Fig. 4 is a rear view of the same.

50 Fig. 5 is a partial view showing the hinge joints.

Fig. 6 is a cross-section enlarged showing one hinge joint with the friction washers.

Fig. 7 shows another spring for the holder. The device comprises essentially a 55 band adapted to engage the hand adjacent the knuckles, and a holder that is hinged to the band, and which is provided with means to removably engage a blotter, whereby the blotter can be swung from a position extending forward under the fingers, to a position 60 extending rearward against the rear of the palm and the wrist.

As shown I provide a band 2 somewhat in the form of an ellipse but with the ends 65 separated a considerable distance. This band is made of spring metal of a size to slip on the back of the hand slightly beyond the knuckles, with the free end portions projecting across the middle portion of the palm 70 a short distance, which will serve to retain the device on the hand, yet permit easy application and removal.

I further provide a holder member to readily engage a piece of blotting paper, 75 denoted by 3, comprising a pair of jaws that may be formed by simply doubling back a piece of sheet metal somewhat resilient. These jaws 4 and 5 at their bend are provided with lugs 6 and 7 that enter apertured 80 ears 8 and 9 on the back of the band 2 as shown. Preferably these ears are part of a strip 10 that has its edges 11 bent around the band 2 to secure it thereon. It will thus be seen that the holder jaws swing on this 85 pivotal axis on the back of the band, which axis will extend longitudinally of the band or transverse to the hand of the user. This will permit the blotter to be swung from a position extending rearward under the palm 90 and wrist, to a position extending forward under the fingers to be caused to blot the written matter, as illustrated.

To facilitate the swinging of the blotter from the rear position to the forward position, I provide an arm or lug 12 that will extend down from the jaw 4 when the blotter is in the rear position, and can be engaged readily by the third finger of the user, while the pen is still held by the thumb and 100 first and second fingers of the hand. Obviously the same finger, after the blotter

has been used will simply press down on the blotter and return it to its rear position out of use, while the pen is still held by the fingers as stated.

5 To retain the blotting strip 3 in the jaws 4 and 5, I arrange a nut member 13 on one jaw 5, and the opposite jaw 4 has an aperture 14, through which a screw 15 passes and engages the nut 13, whereby to draw the 10 jaws together and clamp the blotter 3 in the jaws. These jaws are preferably of resilient metal and will be spring pressed together, and to open them to insert the blotter, I provide ears 16 and 17 on the upper apertured jaw 4, so that by engaging these ears with two fingers, and pressing on the screw, previously loosened in the nut, the other jaw will be forced away from this jaw to 15 permit the ready insertion of the blotting 20 strip; that on release of these parts will be retained by the jaws, and thereupon the screw is tightened to secure the blotter in the jaws.

I have further discovered the blotting 25 strip in the rear position should be offset slightly to the outside of the hand, away from the thick portion of the palm adjacent the thumb. This is effected by so arranging the journal lugs that the pivotal axis is on 30 a slight axis to the plane of the band, as indicated in Fig. 4, and forming one ear as 16 higher than the other ear.

Means are also preferably provided at the hinge to retain the holder and blotter in each 35 of the said positions to which these swing, and thus prevent the blotter from falling to a downwardly or vertical position. One means of retaining the holder in each position, is to provide a washer 19 having a slot 40 to slide on the flat journal portion 6 at the joint to prevent it from turning therewith. The washer is grooved transversely as shown in Fig. 5 and is pressed by a coil spring 18 against a similarly grooved portion of the 45 ear 8 in which the journal portion 6 turns. It will be seen that in either of the two horizontal portions of the holder and blotter the spring will force the grooved washer into the grooved ear tending to retain it in such 50 position, but when the holder is swung the washer can move back and compress the spring, but when fully swung will again cause the washer to engage the ear on the groove.

55 In Fig. 7 I show another form of spring arrangement to retain the holder in the two engaging positions, that comprises merely a spring strip 29 carried by the strip 10, that engages the flat faces of the jaw pieces 4 and 5, and will be depressed as the holder is 60 swung up from either position.

It will be further observed that the band 2 is formed of two parts 21 and 22, that are 65 engaged by the bent flaps 11 of the holder frame, see Fig. 4; the two portions lapping

in this holder, that permits them to have a sliding action whereby the ends of the band can be drawn further apart or brought closer together, for the purpose of adjustment for different sizes of the hand of the user. The 70 lapping parts will be held by strips in the adjusted positions.

What I claim is:

1. A hand blotter comprising a spring band in the form of an open loop adapted to 75 encircle the hand, and a blotter holder hinged to the band to swing on an axis transverse to the hand, whereby the blotter can be swung from a position adjacent the fingers to a rearward position adjacent the 80 wrist, and means for retaining the holder with the blotter in each of the two said positions.

2. A hand blotter comprising a spring band in the form of an open loop adapted to 85 encircle the hand, and a blotter holder hinged to the band to swing on an axis transverse to the hand, whereby the blotter can be swung from a position adjacent the fingers to a rearward position adjacent the 90 wrist, and a lug on the holder projecting outward in position to be engaged by the fingers of the user when the blotter is against the wrist to swing the blotter to the said forward position for use. 95

3. A hand blotter comprising a band adapted to encircle the hand, and a blotter holder hinged to the band to swing from a forward position adjacent the fingers to a rearward position adjacent the wrist, said 100 holder comprising a pair of clamping plates to grip the blotter, a nut member on one blade, the other blade having an aperture, a screw that is passed through said blade to engage the nut member and clamp the blades 105 together, said apertured member having one or more ears to be engaged by the fingers to open the blades by pushing on the screw when loosened in the nut.

4. A hand blotter comprising a band 110 adapted to encircle the hand, and a blotter holder hinged to the band to swing from a forward position adjacent the fingers to a rearward position adjacent the wrist, the axis of the holder extending at a slight angle 115 with the plane of the band whereby the holder and blotter will extend toward one side of the wrist in the rear position of the blotter.

5. A hand blotter comprising a band 120 adapted to encircle the hand, and a blotter holder hinged to the band to swing from a forward position adjacent the fingers to a rearward position adjacent the wrist, and means for retaining the holder with the blotter in each of the two said positions. 125

6. A hand blotter comprising a band adapted to encircle the hand, and a blotter holder hinged to the band to swing from a forward position adjacent the fingers to a 130

rearward position adjacent the wrist, and a lug on the holder projecting outward when the blotter is against the wrist in position to be engaged by the fingers of the user to swing the blotter to the said opposite position for use.

7. A hand blotter comprising a spring band in the form of an open loop adapted to encircle the hand, and a blotter holder

hinged to the band to swing on an axis 10 transverse to the hand, whereby the blotter can be swung from a forward position adjacent the fingers to a rearward position against the wrist, said loop having lapping portions for adjustment of width. 15

Signed at Newark, New Jersey, on January 17th, 1922.

THOMAS A. HUTCHINSON.
